[57] CLAIM

The ornamental design for a jewelry bale, as shown and described.

DESCRIPTION

FIG. 1 is an enlarged, perspective view of the jewelry bale showing our new design;

FIG. 2 is a front elevational view thereof;

FIG. 3 is a side elevational view taken from the right side thereof, the left side elevational view being a mirror image of the right side elevational view;

FIG. 4 is a rear elevational view;

FIG. 5 is a bottom plan view thereof; and,

FIG. 6 is a top plan view thereof.
